Primary Examiner — Cynthia Ramirez

Assistant Examiner — Michael A Maharajh

(57) **CLAIM**

The ornamental design for a vibrator, as shown and described.

DESCRIPTION

FIG. 1 is an isometric view of the vibrator showing my new design;

FIG. 2 is a left view thereof;

FIG. 3 is a right view thereof;

FIG. 4 is a top plan view thereof;

FIG. 5 is a bottom view thereof;

FIG. 6 is a front view thereof; and,

FIG. 7 is a rear view thereof.
